UNITED STATES PATENT OFFICE

116,066

DESIGN FOR A COMBINED STOPPER AND FINGERNAIL POLISH BRUSH

Madeline C. Twomey, Brookline, Mass.

Application December 27, 1938, Serial No. 82,008

Term of patent 3½ years

To all whom it may concern:

Be it known that I, Madeline C. Twomey, a citizen of the United States, residing at Brookline, county of Norfolk, State of Massachusetts, have invented a new, original, and ornamental Design for a Combined Stopper and Fingernail Polish Brush, of which the following is a specification, reference being had to the accompanying drawing, forming part thereof.

Fig. 1 is a face view of a combined stopper and fingernail polish brush embodying the invention; and

Fig. 2 is an edge view of the same.

I claim:

The ornamental design for a combined stopper and fingernail polish brush, substantially as shown.

MADELINE C. TWOMEY.
